UNITED STATES PATENT OFFICE.

CHARLES H. BORDEN, OF HARTFORD, CONNECTICUT.

UMBRELLA ATTACHMENT.

1,007,669.

Specification of Letters Patent.

Patented Nov. 7, 1911.

Application filed October 19, 1910. Serial No. 587,946.

To all whom it may concern:

Be it known that I, CHARLES H. BORDEN, a citizen of the United States, residing at Hartford, in the county of Hartford and 5 State of Connecticut, have invented a new and useful Improvement in Umbrella Attachments, of which the following is a specification.

This invention relates to a device which is 10 adapted to be attached to the rod of an umbrella, near the inner end of the handle, or to the tip near the end of a rib, for the purpose of binding and temporarily holding close against the rod or handle, the tips of 15 the umbrella ribs.

The object of the invention is to provide a 20 very simple, cheap, inconspicuous and easily operated device of this nature which can be readily attached to the rod of any of the 25 common types of umbrellas, or to a rib-tip of such umbrellas, and can be quickly used to bind the tips together, when the umbrella is to be carried closed, and instantly released to free them, so that the umbrella can be 30 opened.

The invention resides in an article for this 35 purpose which has a clip that is designed to be sprung upon or fastened to an umbrella rod or rib-tip. The clip has an arm and attached at one end to this arm is a flexible binder, that may be formed of a silk or other cord, or a chain of links or balls. The free end of the binder is adapted to be wound around the rib-tips and engaged with the 40 arm for binding and temporarily holding the rib-tips close together.

Figure 1 of the accompanying drawings shows on an enlarged scale, a plan of an 45 article which embodies the invention. Fig. 2 shows a side view of the same.

The circular clip 1 is desirably stamped or otherwise cut from thin sheet metal, as steel, brass or bronze, having the requisite characteristics to cause it, when bent to the proper 50 shape, to clasp and hold itself in place on the rod of an umbrella, adjacent to the inner end of the handle, or on the tip of a rib—the size of the clip, of course, depending upon the part to which it is to be attached. 55 Extending from one end of the clip is an arm 2. This arm may be doubled upon itself to form two thicknesses, as shown in Fig. 1.

In one form of the invention a finger 3 is

made at the outer end of the arm by bending 55 up in the necessary manner a strip of the metal from which the clip and arm are formed. This provides a slot into which the free end of the binder is passed and held between the end of the arm and the finger. 60

The binder may consist of a silk or other braided cord 5 that has one end permanently attached to the arm. Such a binder is desirably provided with one or more stops which may be knots, balls, or other ornaments or 65 fasteners 6, as shown in Fig. 1. The fixed end of the cord may be knotted between the two thicknesses of the arm.

The clip is easily sprung upon and caused 70 to clasp the steel rod of an umbrella near the inner end of the handle, or upon the tip of a rib. If the arm is provided with a projecting finger, as is shown in Figs. 1 and 2, when it is desired to hold the tips of the ribs 75 close to the rod, the binder is wound tightly around the tips and passed into the slot between the finger and the end of the arm, as illustrated by dotted lines in Fig. 1. The finger may be so bent as to grip the binder sufficiently tight to prevent its slipping, or a 80 knot or ball may be arranged on the binder in position to engage the arm and finger and prevent the binder from slipping and loosening the ribs.

This device is very simple to make and is 85 readily attached to any ordinary form of umbrella. It is small, inconspicuous, and adjustable so it can be used with umbrellas of any size. It can be quickly made to bind the tips of the umbrella ribs and hold them 90 closely against the rod in an attractive manner, obviating wrapping up the cover and binding it with the usual fastener. It can be quickly released to free the ribs, and may be so made that it is ornamental when dangling from an umbrella handle. 95

The invention claimed is:

An attachment for temporarily binding umbrella tips, comprising a spring clip shaped to clasp the supporting rod, said clip 100 having at one end thereof a part bent outwardly and returned upon itself in spaced relation with the outwardly bent part to form a double radial projection adapted to extend between the tips of the umbrella ribs, 105 said returned portion having a cord aperture therein, a spring finger formed integrally with the said projection and bent so

as to extend parallel to and in front of the doubled end of said projection, whereby a cord may be clamped against said doubled end of the projection by the spring finger, 5 and a flexible non-elastic cord having one end thereof extending through said aperture, whereby this end may be secured be- tween and concealed by the walls of the pro- jection.

CHARLES H. BORDEN.
